UNITED STATES PATENT OFFICE

1,971,830

SWITCH CONTACT STRUCTURE

George Pailin, Manchester, England, assignor to
 General Electric Company, a corporation of
 New York

Application October 19, 1929, Serial No. 400,987
 In Great Britain January 9, 1929

4 Claims. (CL 173—363)

My invention relates to electrical switch contact structures, and more particularly to disconnecting switch contact structures of the plug and socket type.

5 In a switch contact structure of the plug and socket type, it is extremely difficult to obtain and maintain a uniform pressure between the segments or contacting surface of the plug and its coating socket to make good electrical contact, and it is an object of my invention to provide simple and efficient means for ensuring such uniform pressure and for exerting sufficient pressure between the plug and socket to effect good electrical contact when the switch is in 15 the closed circuit position.

A further object of my invention is the provision of plug and socket connections wherein the plug member has incorporated therein means for effecting an expansive action on the contacting end of the plug for increasing or regulating the contact pressure between the plug and its coating socket in the closed circuit position.

My invention will be more fully set forth in the following description referring to the accompanying drawing, and the features of novelty which characterize my invention will be pointed out with particularity in the claims annexed to and forming a part of this specification.

Referring to the accompanying drawing; Fig. 30 1 is an elevational sectional view showing a switch of the plug and socket type constructed in accordance with my invention; Fig. 2 is a sectional plan view taken along the line A—B of Fig. 1, and Figs. 3 and 4 are elevational sectional views illustrating a modified form of my invention with the parts in different positions.

Referring to Figs. 1 and 2, the plug member 1 forming one contact of the switch is split or divided at its operative or contacting end, as illustrated, into a number of segments 2, and is adapted to enter within the coating socket member 3 forming the other contact to make electrical connection therewith. The slits forming the segments 2 are so spaced that expansive pressure within the contacting end of the plug is effective to expand the said end, thereby increasing the contact pressure between the same and the socket member. Within the contacting end of the plug 1 is arranged wedging means, as 45 the cones 4 and 5 having their apices adjacent or directed towards one another, one of the cones 4 being fixed upon a rod or stem 6 and the other cone 5 being slidably mounted thereon. The movable cone 5 is normally biased by resilient means, as the spring 7 disposed around the stem

6, so that it is urged towards the fixed cone 4. The other end of the spring is adapted to seat upon a stationary support at the opposite end of the plug.

The annular space between the surfaces of the 60 cones 4 and 5 and the internal surface of the plug segments 2 is filled in with suitable pressure-transmitting material as the balls 8. The tension of the spring 7 may be adjusted to suit the particular operating requirements. 65

It will be apparent that the spring 7 which normally biases the cone 5 and the pressure-transmitting material so as to exert an expansive or radial pressure within the contacting end of the plug is effective to maintain a uniform contact pressure between the plug and its coating socket in the closed circuit position, and that this pressure may be varied by simply varying the tension of the spring 7. 70

Referring now to Figs. 3 and 4, there is illustrated a modified form of my invention wherein the pressure, instead of being applied permanently to the plug segments, may be varied or removed altogether. To this end the hand wheel 9 is provided with a screw threaded shaft 10 which 75 engages at its free end the plunger or equivalent element 11, in turn bearing upon a cross key 12. The key 12 is transversely mounted with respect to the lower end of stem 6 and extends through elongated slots 12a therein so that it is capable 80 of longitudinal movement along said stem. The key 12 is also provided with a collar or the like, 13, upon which the lower end of the spring 7 seats. 85

With this arrangement the pressure upon the plug segments may be released when the plug is to be withdrawn from or inserted in the socket by rotating the handwheel 9 in such direction that the tension on spring 7 is released, as illustrated in Fig. 4, and applied by rotating the handwheel in the opposite direction when the plug is within the socket, as illustrated in Fig. 3. 90

As illustrated in Fig. 4, the fixed cone 4 serves as a guide for the movable cone 5, and the same have their abutting edges spaced in the pressure releasing position of the cone 5. 95

It shall be understood that my invention is not limited to the specific construction herein illustrated, and by way of example more than one pair of cones may be longitudinally arranged within a single plug member if desired, and the means for biasing the movable cone may be varied to suit the particular requirements without departing from the spirit of my invention. 100

110

What I claim as new and desire to secure by Letters Patent of the United States, is:

1. A contact structure of the plug and socket type comprising a socket member, a coacting hollow plug member, a pair of cone-like elements mounted within the contacting end of said plug, said elements being disposed with their apices adjacent each other, pressure-transmitting material disposed between the surfaces of said elements and the inner surface of said plug member, and resilient means for biasing one of said elements towards the other to effect a wedging action on said pressure-transmitting material whereby that end of the plug is expanded into good contacting engagement with its coacting socket member.
2. A contact structure of the plug and socket type comprising a socket member, a hollow plug member, a pair of cone-like elements mounted within the contacting end of said plug in inverted relation with respect to each other, a plurality of balls disposed in and filling the annular space between said elements and the inner surface of the plug, a guide member on which one of said elements is slidably mounted, and a spring disposed about said guide member and bearing against the aforesaid slidably element, the tension of said spring being effective to transmit pressure by way of said slidably element and balls to expand said plug, thereby ensuring good electrical contact between the plug and socket members.

3. A disconnecting switch contact structure comprising relatively movable plug and socket members, means for maintaining a uniform contact pressure between said members in the closed circuit position, comprising pressure-transmitting means wholly contained within said plug member for applying a radial expansive pressure to the contacting end of the plug member, resilient biasing means for exerting a uniform pressure on the aforesaid means, and means adjustable in the closed circuit and operative position of said contact structure for varying the bias of said resilient means when said plug and socket members are to be separated.

4. A disconnecting switch contact structure comprising a socket and a hollow plug member coacting therewith, means for varying the contact pressure between the plug and socket, comprising a pair of coacting wedging members wholly disposed within said plug and relatively movable for applying a radial expansive pressure to the contacting end of the plug member, resiliently biased means adapted to exert pressure on one of said wedging members, and means adjustable for decreasing the bias on the aforesaid means when the plug member is to be removed from its coacting socket, and for increasing the bias when the plug and socket are in operative engagement with each other.

GEORGE PAILIN.
